UNITED STATES PATENT OFFICE.

FREDERICK T. BROSI, OF SAN FRANCISCO, CALIFORNIA, ASSIGNOR, BY DIRECT AND
MESNE ASSIGNMENTS, TO A. W. HIGGINS, TRUSTEE.

BABY-SHOE KEEPSAKE.

Application filed January 20, 1925, Serial No. 3,587. Renewed April 18, 1927.

The present invention relates to the art of making useful keepsakes of baby shoes and resides in the provision of a treatment and construction whereby a baby shoe may be 5 metallized and incorporated with other elements so that there will be provided a useful and ornamental article such as a receptacle, a base for lamp stand, etc., a candlestick holder and many other useful articles.

10 One of the objects of the invention is to provide for the preservation of a baby shoe in its natural form wherein all of the characteristics such as the wrinkles, worn out portions, misshapen parts, etc., will be permanently preserved and manifested in the finished article.

A further object of the invention is to provide a simple and effective means adapted to be incorporated with a baby shoe after the 20 latter is metallized, whereby the ready and effective addition or incorporation with the shoe of extraneous elements such as will convert the shoe into a useful article may be carried out.

25 With the above mentioned and other objects in view, the invention consists in the novel construction and combination of parts hereinafter described, illustrated in the accompanying drawings, and set forth in the 30 claim hereto appended, it being understood that various changes in the form, proportion, size and minor details of construction within the scope of the claim may be resorted to without departing from the spirit 35 or sacrificing any of the advantages of the invention.

Referring to the drawing:

Fig. 1 represents a perspective view of an ordinary baby shoe.

40 Fig. 2 represents a baby shoe after it has been metallized in accordance with this invention and provided with means adapting the shoe to a useful purpose.

Fig. 3 represents a vertical sectional view 45 of a baby shoe which has been metallized, mounted on a base incorporated with other elements to provide a useful article such as an ash tray or other receptacle.

Fig. 4 represents a longitudinal sectional 50 view taken through the device of this invention showing the baby shoe metallized mounted on a base and adapted to serve as an ink well.

Fig. 5 represents a fragmentary vertical 55 sectional view of the upper part of the shoe

treated in accordance with this invention and adapted to serve as a vase or candlestick holder.

In carrying out this invention an ordinary baby shoe, whether it be constructed of 60 leather or other material, is first treated with paraffine or any other suitable substance which will make the shoe stiff enough to retain the form or arrangement desired to be preserved and manifested in the finished product. After the treatment above 65 described, the shoe parts are bent or arranged as desired, for example, the toe may be bent upward, or the tongue made to hang out, or the upper part may be irregularly 70 arranged. Next the shoe is metallized in any suitable manner, preferably by an electroplating process, and is then ready to be constructed so that it may serve as a useful article. 75

In order to adapt the shoe after metallizing for use as a stand, support, a receptacle, standard or anchorage, for example, so that there may be provided an ash tray, an ink well, a candle-stick holder, lamp base, etc., 80 I provide a means to be attached to the upper margin of the top part of the shoe. This means, as shown in Figs. 2 and 4, comprises an annular member 1; in Fig. 3, an annular flange-like member 2; and in Fig. 5, a 85 flanged cap member 3. The annular member 1, as shown in Figs. 2 and 3, in combination with the shoe, provides a socket in which may be fitted a receptacle 4, as shown in Fig. 4. Any other device such as a stand- 90 ard for a lamp or any other element may be fitted in said socket. The annular member 1 defines an opening for the socket of a definite shape and provides for the incorporation of an element with the shoe for the 95 purpose of providing a useful article. This member 1 is welded or otherwise permanently secured to the upper edge of the shoe so that it becomes a part of the shoe and acts as a shape defining, attaching and reinforcing 100 element. To provide for an effective joining of the ring member 1 with the upper part of the shoe, said member is formed substantially semicircular in cross section and from its upper edge there depends an annular 105 flange 5, extending laterally and inwardly from the lower end of which is a horizontal annular flange 6. This flange 6 is disposed well above the lower edge of the ring and is adapted to rest upon the upper edge of the 110

top of the shoe (see Fig. 4). The lower edge of the ring will engage the outer side of the substantially circular top portion of the shoe at a point below the upper edge of said top.

- 5 At these points where the ring engages with the shoe, the ring is welded or otherwise permanently secured thereto. By employing a ring of this shape, provision is made for a neat and strong joint between the top of the 10 shoe and the ring and a socket is formed in this upper portion of the shoe, which socket may be used in incorporating other elements with the shoe. The ring may also serve as an anchorage for any other element, (not 15 shown) to be incorporated with the shoe.

As shown in Fig. 3, the annular flange member 2 extends beyond, outwardly and downwardly from the outer edge of a cup or like receptacle 7, which receptacle is adapted 20 to extend into the upper end of the shoe and may, as shown, be fastened to the inner side of the bottom of the shoe and to a base plate 8 on which the shoe may be mounted by means of suitable fastening elements, as 25 shown at 9. This cap is fastened to the shoe so that the upper edge of the shoe will engage beneath the flange close to the point where the latter is joined to the upper edge of the cap and the metallized shoe and flange 30 may be welded or otherwise fastened together where thus engaged.

- 35 As shown in Fig. 5, the member 3 is in the form of a flanged cap in which the flange 10 is welded or otherwise joined as at 11, to the metallized shoe 12 at a point below the upper edge of the top of said shoe. The top of the shoe will engage the substantially horizontal top part of the flanged cap. Carried by the cap 3 as shown in Fig. 5, is a 40 socket 13 which may serve as a vase or candle-stick holder or put to any other use for which such member is capable of use. The cap 3 serves the same purpose as the members 1 and 2, shown in Figs. 2, 3 and 4.
- 45 The baby shoe as shown at A, in Fig. 1, after being metallized is not in such form that would permit of a ready and effective incor-

porating with the shoe, some element or elements such as would convert the shoe into a useful article, for example, a vase or candle-stick holder, ink stand, etc. The raw upper edge of the top of the shoe is not suitable for use without incorporation therewith of the elements 1, 2 and 3, as shown in the drawing. By the use of these elements or 55 other elements of substantially the same arrangement, form or construction, which elements are permanently joined and act as margins for the upper edge of the shoe, the shoe is adapted for useful purposes and for 60 the incorporating therewith of elements such as would make a useful article of the shoe.

One of the advantages of the invention is the provision for making a permanent ornamental keepsake of an ordinarily de- 65 structible baby shoe which in its natural form is unsuited for service as a stand, support, etc., and to at the same time provide for converting the baby shoe into a useful article. The permanency and use of the shoe 70 for the purposes mentioned is made possible by the metallizing of the shoe. The metallizing of the shoe without destroying any of the characteristics such as the wrinkles, worn portions and other desirable features renders 75 the finished article more ornamental and lasting as a keepsake or memento. Through use of the elements 1, 2 and 3, provision is made for an easy and effective adaptation of the shoe to a useful purpose and for the in- 80 85 incorporation of the shoe with such extraneous elements as will convert the shoe into a useful article as well as reinforcing the finished article and making it more lasting and durable.

I claim:

A metallized baby shoe provided with means for incorporating therewith an element which will convert the shoe into a useful article, which means comprises a member adapted to be joined with and extended over the upper edge of the top of the shoe. 90

FREDERICK T. BROSI.
